UNITED STATES PATENT OFFICE.

JOHN SCHUMACHER, OF LOS ANGELES, CALIFORNIA.

PLASTER-BOARD LATH.

Application filed August 6, 1923. Serial No. 656,012.

To all whom it may concern:

Be it known that I, JOHN SCHUMACHER, a citizen of the United States, and resident of Los Angeles, in the county of Los Angeles and State of California, have invented new and useful Improvements in Plaster-Board Lath, of which the following is a specification.

This invention relates to an improved article of manufacture, and the primary object thereof is to provide a plaster board lath for use in conjunction with a cementitious wall coat, and which is arranged to lock or key the coat in place. Another object of this invention is the provision of a lath of the character above described which is simple in structure, inexpensive to produce, durable, and strong.

These objects together with other objects and corresponding accomplishments are obtained by means of the embodiment of my invention illustrated in the accompanying drawing, in which:

Fig. 1 is a face view of a fragment of a sheet or slab of plaster board lath constructed in accordance with the present invention; and Fig. 2 is a section as seen on the line 2—2 of Fig. 1.

Referring more particularly to the drawing, the improved plaster board lath is produced in accordance with any preferred method or process, and is formed in the usual manner of a body or filler 3 disposed between face sheets 4 and 5 of paper or like material. The body or filler is preferably formed of cementitious material, and the face sheets are preferably formed of a paper slowly permeable to moisture. However, the article is in no way limited to this precise structure. Such plaster board is well known in the art, and the present invention appertains particularly to a modification or alteration of the surface of the board. It is well known that in order to perform the function of holding the plaster coating to the board or lath, the surface of the latter adapted to receive the plaster coat must be provided with suitable irregularities for the reception of the latter.

In order to provide such irregularities, I have provided pockets by cutting tongues

in the face sheet 5, indenting the tongues and depressing the body filler so as to form recesses. In forming the recesses, undercut walls 7 are preferably formed at the tips of 55 the tongues, as indicated by 8 in Fig. 2. An advantageous way to produce the pockets is to cut the tongues before the plastic filler is introduced between the face sheets, and then to depress the tongues while the filler is in a 60 plastic condition.

The finished plaster board lath is applied to the walls of the building structure preparatory to receiving the plastic or cementitious wall coating. This coating may be 65 applied to the lath in any suitable manner, the face thereof which is provided with the indentations is disposed to receive the plaster. Plaster is applied to the lath in any suitable manner and being in a plastic or mobile state, it will intrude into the recesses, filling the latter and will eventually harden and set within such recesses so as to lock the coating to the lath. This causes the plaster coating to be effectively supported and retained.

It is obvious that the grouping of the pockets or indentations may be made in any desired manner. Thus, those shown in the drawing consists of rows, the pockets in one 80 row being staggered with relation to the pockets in the adjacent rows.

What I claim is:

1. A plaster board having a plurality of pockets therein adapted to receive intruding 85 portions of a plaster coat in interlocking engagement therewith; said board having a cementitious body and covering sheets, one of said covering sheets being slit to form pocket openings and the portion defined by 90 the margin of said openings being depressed to form pockets having an undercut wall the covering sheet being indented to form the bottoms of said pockets.

2. A plaster board having a plurality of 95 pockets therein adapted to receive intruding portions of a plaster coat in interlocking engagement therewith; said board having a cementitious body and covering sheets, one of said covering sheets being slit to provide 100 tongues and indented to form the inclined bottoms of pockets.

3. A plaster board having a plurality of pockets therein adapted to receive intruding portions of a plaster coat in interlocking engagement therewith; said board having a 6 cementitious body and covering sheets, one of said covering sheets being slit to provide tongues and indented to form the inclined

bottoms of pockets having undercut exposed walls opposite the tongue tips.

In witness that I claim the foregoing I 10 have hereunto subscribed my name this 28th day of July, 1923.

JOHN SCHUMACHER.
